UNITED STATES PATENT OFFICE

2,475,124

FRAME FOR NAILING MACHINES

Harry D. Benson, Fresno, Calif., assignor to General Nailing Machine Corporation, Sanger, Calif., a corporation of California

Application June 6, 1947, Serial No. 752,974

5 Claims. (Cl. 1—10)

1

This invention is directed generally to box nailing machinery.

One object of the present invention is to provide a novel frame for a nailing machine; such frame being, in the main, of sheet metal fabricated in a manner to provide strength and rigidity without undue weight.

Another object of the invention is to provide a nailing machine frame, as above, which is designed for ease of manufacture or assembly from a relatively small number of preformed sheet metal parts; said parts being secured together, as by welding, into a unitary structure.

An additional object of the invention is to provide a unitary sheet metal frame, for the purpose described, which is fitted—in novel combination—with certain heavy-duty metal members rigidly mounted in the frame and adapted to carry or support the working parts of the nailing machine.

A further object of the invention is to provide a simple, inexpensive, and practical frame for nailing machines, and yet one which will be exceedingly effective for the purpose for which it is designed.

These objects are accomplished by means of such structure and relative arrangement of parts as will fully appear by a perusal of the following specification and claims.

In the drawings:

Fig. 1 is a sectional elevation of the improved frame for nailing machines.

Fig. 2 is a fragmentary sectional plan on line 2—2 of Fig. 1.

Fig. 3 is a transverse section on line 3—3 of Fig. 1.

Fig. 4 is a fragmentary sectional plan on a line 4—4 of Fig. 1.

Referring now more particularly to the characters of reference on the drawings, the nailing machine frame comprises a pair of vertical, transversely spaced side legs, each of which is indicated generally at 1. These side legs are formed of sheet metal, each being of channel configuration, tapering somewhat from bottom to top, and facing laterally inwardly, i. e. opening toward each other.

The outer wall of each leg 1 is indicated at 2, and the spaced-apart side walls are indicated at 3. Along their free edges the side walls 3 are formed with inturned stiffening lips 4 which extend substantially full length of the legs 1.

At the top of the frame the latter is fitted with a preformed sheet metal cap assembly, indicated generally at 5, secured in matching rigid relation with the upper ends of said legs 1, as by welding.

2

This cap assembly 5 is of generally inverted channel shape in cross section.

At the bottom of the frame the legs 1 are connected together in rigid relation by a somewhat U-shaped base 6 having upstanding walls 7 and 8 at opposite ends thereof; said walls 7 and 8 bearing, at their ends, against and being welded to corresponding stiffening lips 4 of side walls 3 of the legs 1.

At their upper edges the walls 7 and 8 are formed with inturned, transverse flanges 9 and 10, respectively, for the purpose of adding rigidity to the structure.

To stabilize the frame on the floor, the legs 1 are fitted, at the bottom thereof, with oppositely projecting hollow feet 11 of prefabricated sheet metal, which feet are welded to said legs.

The above described frame, being formed in its substantial entirety of sheet metal, is relatively light weight, and inexpensive to manufacture; yet provides a sturdy and rigid structure for the support of the working parts or mechanisms of the machine.

With the described sheet metal frame there is included, in novel combination therewith, a plurality of heavy-duty metal members, as herein-after described, for the purpose of mounting or attachment of said working parts or mechanisms, which obviously could not be secured to the relatively light sheet metal of the frame.

These heavy-duty metal members comprise the following:

Adjacent but short of the lower ends of the legs 1, each thereof is fitted with a vertical plate 12 of heavy metal disposed within said leg parallel to its outer wall 2, but resting against the inner face of the stiffening lips 4.

These plates 12 are of heavy-duty, relatively non-bendable metal, and are welded at their ends to corresponding side walls 3; such plates (which are known as the transmission plates) facing each other and being adapted to support, in journaled relation, certain of the rotary mechanisms (not shown) of the nailing machine.

The wall 7 of the U-shaped base 6 is fitted, on the outside, with an inverted U-shaped bracket 13 in which an electric drive motor is adapted to be mounted, with its endless drive extending through a port 14 to the rotary mechanisms adapted to be carried between the heavy-duty plates 12.

Adjacent their upper ends the legs 1 are each fitted with a pair of vertically spaced, horizontal mounting bars 15 which abut the inner face of the stiffening lips 4 in the same manner as the

plates 12; said bars 15 being fixedly secured at their ends to the side walls 3, as by welding.

The pairs of horizontal mounting bars 15 carry therebetween vertical, transversely spaced guide bars 16 which guide vertical reciprocation of the top driver bar 17 of the nailing mechanism. This top driver bar reciprocates relative to posts 18 adapted to carry the nailing units and work supporting nailing tables (not shown). The guide bars 16, top driver bar 17, and posts 18 are indicated in broken lines to illustrate their relative positions within the frame; it not being necessary to here illustrate the nailing mechanism in any great detail.

The plates 12, together with the mounting bars 15, not only serve as a fixed support for certain of the working parts, but they also tend to add further strength and stability to the sheet metal frame.

If desired, cover plates may be attached to the legs 1 on adjacent sides thereof, by securing said cover plates to the stiffening lips 4.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A nailing machine frame comprising a pair of spaced apart legs, each leg consisting of relatively light sheet metal and being of channel

shape to provide an outer wall and two side walls, the free edges of the side walls being inturned to form narrow stiffening lips, the open sides of such channel shaped legs being disposed in facing relation, a cap connecting the upper ends of said legs, a base, such base consisting of relatively light sheet metal and of inverted U-shape in cross section, such base projecting between the legs, and the ends of the base being secured to the insides of the legs adjacent the inturned lips.

2. A frame as in claim 1, including an inturned flange formed on the upper edge of each of the side walls of the base.

3. A structure as in claim 1, including a sheet metal bracket of inverted U-shape secured to one wall of the base, such wall being provided with an open port adjacent one end of the bracket.

4. A frame as in claim 1 including a rigid heavy duty metal plate extending across from and secured to the side walls adjacent the inturned lips on each leg adjacent the lower ends of said legs.

5. A frame as in claim 4 and including spaced apart heavy duty rigid bars extending across from and secured to the side walls adjacent the inturned lips of each leg adjacent the upper ends of said legs.

HARRY D. BENSON.
